Primary Examiner — Cynthia R Underwood*(74) Attorney, Agent, or Firm* — Brooks, Cameron & Huebsch, PLLC(57) **CLAIM**

The ornamental design for a control enclosure, as shown and described.

DESCRIPTION

FIG. 1 is a perspective view of the control enclosure; FIG. 2 is a front elevation view thereof; the rear forming no part of the claim;

FIG. 3 is a left side elevation view thereof, the right side elevation view being a mirror image thereof.

FIG. 4 is a top plan view thereof; and,

FIG. 5 is a bottom plan view thereof.

The broken lines in the drawings depict subject matter of the control enclosure that forms no part of the claimed design.

1 Claim, 3 Drawing Sheets(56)
